SIGNORS TO UNITED PRODUCTS COMPANY, INC., OF LOS ANGELES, CALIFORNIA, A
CORPORATION OF CALIFORNIA.

DIE.

Application filed January 27, 1926. Serial No. 84,046.

This invention relates to dies and is more particularly directed to a die for use in connection with a machine for compressing cellulosic material to produce fuel.

5 In the compressing of cellulosic material to produce compact briquettes, it has been heretofore supposed that dies having restricted sections must be employed so that the finely divided cellulosic material would 10 pack in the die and both this restricted section and the cellulosic material would not be simply pushed or crowded through the central bore of the die. We have discovered, however, that if the die be increased in 15 length sufficiently that it is not required to provide a restricted central section of the die or variable means for providing variation restrictions of the central section of the die, and we have further discovered that 20 the compactness or density of the fuel produced through such a die may be easily regulated by the length of the die employed so that when it is desired to produce a very compact cellulosic material a long die is 25 employed, that is long relative to the stroke of the plunger or piston acting in conjunction with the heat employed to produce the cellulosic fuel. If a fuel is desired which is not of too great compactness a shorter 30 die may be employed. It is not believed that there is a minimum or maximum of length of die that can be employed other than the possible minimum of providing a die which is greater than twice the length of the stroke 35 of the piston or plunger.

It is therefore an object of this invention to produce a die for use in connection with machines for compressing cellulosic material to produce fuel that has a straight or substantially straight central bore and which is of such length that the cellulosic material will be jammed therein and will become compressed on the stroke of the piston acting in conjunction with the heat imparted to the die and hence to the cellulosic material within the central bore of the die.

It is a further object of this invention to provide a die having a plurality of bores therein through which portions of the cellulosic material being pressed in the die combustible gas and steam produced during the process are exuded into a stove surrounding the die and which portions of the cellulosic material and gas are ignited to provide the

heat required for the production of the cellulosic fuel. 55

Other objects and advantages of this invention will be apparent from the following detailed description of a preferred embodiment thereof, as illustrated in the accompanying drawings, in which drawings:

Fig. 1 is a side elevation partly in section of a cellulosic fuel compressing machine illustrating in central sectional side elevation dies embodying this invention as adapted for use in conjunction therewith. 65

Fig. 2 is an enlarged sectional side elevation of a fuel die embodying this invention, illustrating the same as secured to a fragment of the compressing machine and 70 illustrating likewise in side elevation a stove surrounding the die.

Fig. 3 is an end elevation taken substantially on the line 3—3 of Fig. 2.

In the preferred embodiment of this invention illustrated in the accompanying drawings, 1 illustrates a standard upon which a frame 2 is supported. Supported in the frame 2 is a shaft 3 driven through a gear 4 which meshes with a pinion gear 5 80 mounted upon a shaft 6 driven from a source and through connections not herein illustrated. An eccentric 7 is secured to the shaft 3 and is pivotally connected to a sliding block 8 by means of a pin 9. The sliding block 8 travels in a yoke 10 of the Scotch yoke type which yoke 10 is connected by means of rods 11 to pistons or plungers 12. 85

13 illustrates a feed spout into which finely divided cellulosic material, such as sawdust, shavings, or the like, are permitted to fall into the chamber 14 in front of the piston 12 from which chamber 14 the material is forced into the die 15. The die 15 comprises a cylinder 16 having a central straight bore 17 formed therethrough. A plurality of bores 18 are formed in the die providing a communication between the central bore 17 and the exterior of the die 15. The bores 18 are preferably inclined rearwardly or 90 against the direction of travel of the fuel through the die this being so that not too great a portion of the cellulosic material forced into the die will be exuded through the ports or bores 18. A catcher 19 is 95 mounted upon the exhaust end of the die 15 to catch the briquettes as the same are expelled from the interior of the die on the 100 105

compression stroke of the plunger 12. This catcher comprises a plurality of spring fingers 20 which act merely to retard the force of expulsion of the briquettes from the central bore 17 of the die. The catcher 19 is secured to the forward end of the die 15 by any suitable means, such as illustrated at 21.

A stove 22 completely surrounds the die 15 and a gas burner 23 is mounted within the stove 22 and is supplied with gas through a valve conduit 24 from any suitable source. A smoke stack 25 is provided to carry away the products of combustion formed within the stove 22. The operation of the die 15 is as follows:

The burner 23 is first set into operation to heat the die. The plunger 12 is then set in operation and cellulosic material dropped into the feed spouts 13. The end of the plunger 12 then forces the fuel from the chambers 14 into the central bore 17 of the die. On successive strokes of the plunger 12 the finely divided cellulosic material becomes wedged within the central bore 17 of the die and upon continued operation the cellulosic material is compressed, during which compression portions of the cellulosic material compressed within the central portion of the bore 17 are exuded from the bores 18 and are ignited in the stove 22.

After the machine has been in operation for a sufficient time to raise the die to the requisite temperature, the gas supply to the burner 23 may be discontinued and the material exuded from the bores 18 will burn without the stove 22 to provide the heat required for the compression of the cellulosic material.

The bore 17 of the die 15 is uniform throughout its length and need not be restricted. The length of the die 15 and hence the bore 17 must be greater than twice the length of the piston 12.

We have discovered that bores 18 in the die 15 produce a further and important result during the compression of the cellulosic material in that they provide an avenue of escape from the bore 17 of the die for the steam and gas produced during the compression and heating of the material. Gas pockets formed within the die and the briquettes produced are eliminated. The provision of these bores also eliminates the building up of pressure within the die, which pressure in many instances before the provision of such bores caused the die to act in the nature of a cannon and shot the briquettes from the machine.

Having fully described a preferred embodiment of this invention, it is to be understood that we do not wish to be limited to the exact details of construction herein set forth, which may obviously be varied in de-

tail without departing from the spirit of our invention as set forth in the appended claims.

We claim:

1. A die comprising a cylinder having a central bore and a plurality of ports formed in the bore and communicating with the exterior of the die through which cellulosic material is exuded to heat the die, and a stove surrounding the die. 75

2. A die comprising a cylinder having a bore formed therethrough, a plurality of rearwardly inclined ports formed in the die for establishing communication from the bore to the die to the exterior thereof through which cellulosic material and gas are expelled, and a stove surrounding the die. 80

3. A die comprising a tube having a bore formed therethrough, a plurality of ports for establishing communication from the bore to the exterior of the die through which cellulosic material and gas are expelled, and means secured to the exit end of the die for arresting motion of the cellulosic material when the same is expelled from the die. 85

4. A die comprising a tube having a central bore therein into which a piston is adapted to force cellulosic material under pressure, a stove surrounding the die, a plurality of ports formed in the die through which cellulosic material and gas is forced from the die into the stove to heat the die, and means secured to the exit end of the die for resisting the expulsion of the compressed 100 cellulosic material from the die. 105

5. A die for use in forming compressed cellulosic fuel briquettes from finely divided cellulosic material comprising a tube having a central bore into which the cellulosic material is forced, and spring means secured to the exit end of the die for resisting the expulsion of the compressed material from the die. 110

6. A die comprising a cylinder having a central bore into which cellulosic material is adapted to be forced to form briquettes, and spring means secured to the exit end of the die for arresting motion of the cellulosic material when the same is expelled 115 from the die.

7. A die comprising a cylinder having a central bore and a plurality of ports formed in the bore communicating with the exterior of the die, through which cellulosic material is exuded to heat the die, a stove surrounding the die, and spring means secured to the exit end of the die for arresting motion of the cellulosic material when the same is expelled from the die. 120

Signed at Los Angeles, California, this 19 day of January, 1926.
